MAN'S SOCK

Fred J. Vanhorn, Valdese, and Roy L. Vanhorn,
Drexel, N. C., assignors to Menzies Hosiery
Mills, Inc., Hickory, N. C., a corporation of
North Carolina

Application June 4, 1951, Serial No. 15,387

Term of patent 14 years

(Cl. D47—7)

To all whom it may concern:

Be it known that we, Fred J. Vanhorn and Roy L. Vanhorn, both citizens of the United States of America, residing at Valdese, county of Burke, State of North Carolina, and Drexel, county of Burke, State of North Carolina, have invented a new, original, and ornamental Design for a Man's Sock, of which the following is a specification, reference being had to the accompanying drawing, forming a part thereof.

The drawing is an elevation of the sock showing our new design.

The invention is characterized by a plurality of rectilinear areas of contrasting color to each other and to the body of the sock forming a pair of substantially diamond-shaped areas on each side of said sock, said diamond-shaped

areas being disposed in juxtaposed, off-set relation to each other. The drawing is lined to indicate contrasting colors.

We claim:

The ornamental design for a man's sock, substantially as shown and described.

FRED J. VANHORN.
ROY L. VANHORN.
